UNITED STATES PATENT OFFICE.

FRANK C. BORGMEYER, OF ST. CHARLES, MISSOURI.

MEANS FOR SECURING PICTURE-MOLDINGS TO WALLS.

950,365.

Specification of Letters Patent. Patented Feb. 22, 1910.

Application filed May 18, 1909. Serial No. 496,847.

To all whom it may concern:

Be it known that I, FRANK C. BORGMEYER, a citizen of the United States, residing at St. Charles, in the county of St. Charles and 5 State of Missouri, have invented new and useful Improvements in Means for Securing Picture-Moldings to Walls; and I do hereby declare the following to be a full, clear, and exact description of the invention, such 10 as will enable others skilled in the art to which it appertains to make and use the same.

My invention relates to new and useful 15 improvements in means for securing picture moldings to walls and my object is to provide means for removably attaching the molding in position.

A further object is to provide an anchoring 20 means for holding the molding support in position on the wall.

A further object is to provide means for 25 removably attaching the molding to the supporting device and a still further object is to provide means for adjusting the parts 30 of the molding support, whereby said molding may be placed in proper alinement.

Other objects and advantages will be hereinafter referred to and more particularly 35 pointed out in the claims.

In the accompanying drawings forming 40 part of this application, Figure 1 is a sectional view through a wall, showing a section of molding and the supporting means therefor. Fig. 2 is a front elevation of the 45 molding support, showing the retaining screw thereof in section, and, Fig. 3 is a sectional view as seen on line 3—3, Fig. 1.

Referring to the drawings in which 50 similar reference numerals designate corresponding parts throughout the several views, 1 indicates a wall such as is constructed of bricks or the like and 2 the plaster thereon, while three indicates the skim or finishing coat over the plaster.

55 Embedded in the wall 1 are anchors 4, which may be constructed in any suitable manner, the outer ends thereof being secured to a plate 5 in any preferred manner, as by providing studs 6 thereon, which are introduced through openings in the plate and the protruding ends thereof upset and when the anchors are properly embedded in the wall, the plate 5 will be securely held in position and the outer face thereof flush with the 60 outer face of the skim coat 3, or nearly so.

The plate 5 is provided with an opening 7,

which is preferably square, through which is to be introduced a nut 8, the forward face of the nut being provided with a projection 9, which is adapted to protrude through a slot 10 positioned in the plate, said slot being directed at an incline for properly adjusting or alining the molding 11 when said molding is positioned on the wall.

Attached to the rear face of the plate 5 is a housing 12, which is of such dimension as to loosely receive the nut 8, but so arranged as to prevent undue play of the nut and incidentally hold the nut against rotation, said housing being attached to the rear 70 face of the plate 5 by means of rivets or the like 13 and as said housing fits snugly against the plate, foreign particles will be prevented from entering the housing to retard the movement of the nut. 75

The molding 11 is secured in position by introducing a bolt 14 through an opening in the molding, the inner end of the bolt having threads 15 which are adapted to engage the threaded opening 16 in the nut 80 and it will be readily seen that when the nut is placed in the rear of the plate 5 and the bolt applied as shown, said molding will be securely held in position on the wall.

In applying the molding, the strip of 85 molding is positioned on the wall and marked at the proper point for boring the opening through which the bolt 14 extends and should some of the plates be positioned slightly higher or lower than the remaining plates the opening for the bolt is to be 90 so positioned as to bring the molding 11 in proper alinement throughout its length and this can be readily accomplished in view of the inclined slot 10, for should one 95 of the plates be too low, the nut is to be moved a sufficient distance into the slot 10 to bring the molding in proper alinement when the bolt is engaged with the nut, in which event the nut would be positioned 100 nearer the closed end of the slot and vice versa when the plate is positioned too high.

After the opening for the bolt has been properly bored, the nut is introduced through the opening 7 and moved to the 105 proper position to receive the bolt, when said bolt is turned into the nut, thereby securely clamping the molding into engagement with the plate.

Should for any reason, it be desired to remove the molding, as when papering the wall, the bolts 4 are to be removed and the

molding thus released, when, after the papering is completed, the molding is returned to its proper position and the bolts again engaged with their respective nuts and in view of the fact that the plates are flush with the outer face of the wall, the paper may be pasted over the plate and that portion thereof extending over the opening and slots in the plates, cut out, thereby obviating the necessity of cutting the paper to fit around the plates or cutting the paper in proper length, as when the molding is permanently attached to the wall. It will further be seen that should the molding be put up in sections, as soon as one of the sections has been removed, the bolts in the remaining sections may be slightly loosened and the sections moved longitudinally until the nuts on the bolts register with the openings 7, when the molding may be removed by removing the nuts from engagement with the plates, but in accomplishing this result, the nuts in all the plates would necessarily have to be in the same relative position longitudinally of the plates. It will further be understood that the anchors 4 may be properly arranged to coöperate with a wall constructed of wood or other material of which the wall is constructed.

It will thus be seen that with my improved device, the molding can be quickly applied or removed from position on the wall and without marring or defacing the wall and that said molding will be securely held in position on the wall and with greater rigidity than when applied in the manner as now in common practice and it will fur-

ther be seen that said molding may be retained in proper alinement at all times.

What I claim is:

1. A supporting device for molding comprising a plate, anchoring means for said plate a housing in the rear of said plate, said plate having an opening therethrough and an inclined slot communicating with said opening; a nut adapted to pass through said opening and be seated in said housing, said nut having a threaded opening and a bolt adapted to extend through a molding and engage said nut said nut having a threaded projection adapted to extend into said slot.

2. In a supporting device for molding, the combination with a plate, means to anchor the same on a wall and a housing attached to the rear face of said plate, said plate having an opening therethrough and an inclined slot communicating with the opening, said slot and opening being covered by the housing; of a nut adapted to be introduced through the opening and into the housing, an interiorly threaded projection on the nut adapted to enter said slot and a threaded bolt adapted to extend through a section of molding and engage the threads in the nut to support said molding on the wall.

In testimony whereof I have signed my name to this specification in the presence of two subscribing witnesses.

FRANK C. BORGMEYER.
